UNITED STATES PATENT OFFICE.

JOHN H. TOOF, OF CONCORD, NEW HAMPSHIRE.

STARCHING-MACHINE.

SPECIFICATION forming part of Letters Patent No. 355,232, dated December 28, 1886.

Application filed March 6, 1886. Serial No. 194,263. (No model.)

To all whom it may concern:

Be it known that I, JOHN H. TOOF, a citizen of the United States, residing at Concord, in the county of Merrimac and State of New Hampshire, have invented certain new and useful Improvements in Starching-Machines, of which the following is a specification.

My invention consists in details of construction described below, and pointed out in the 10 claims.

Figure 1 represents a vertical sectional elevation of my improved machine, taken on line $x x$, Fig. 2. Fig. 2 is a general plan of the same.

15 Similar reference-letters indicate corresponding parts in both views. A is a receptacle for starch, which may be formed of some suitable wood, and of any convenient design. B B' b represents an iron 20 frame by which it is supported.

C is a horizontally-reciprocating plunger, formed of some suitable wood, and connected by means of an upright, D, to the piece E, preferably formed of iron or metal, and adapted to 25 rest upon ways F, secured for this purpose upon the top or cover a of the starch-box A at either side of the central slot, a' , through which the upright D is passed.

When the machine is in use, the receptacle 30 A should be kept nearly full of starch, which may be accomplished in some convenient manner through an entrance in the cover a . Motion is transmitted to the plunger C by means of a driving-shaft, a crank, and the following 35 intermediate connections: A rod, G, is connected at one end to the part E and at the other to a projecting lug, h, of the cross-head H, which is mounted upon rods I, supported in bearings formed for this purpose in the 40 transverse parts B' of the frame. Upon the under side of the cross-head H are ears h', between which is fitted one end of a pitman, J, the other end being in the form of a pin playing in the bearing j, connected with the crank 45 K, mounted upon the driving-shaft L, a tight and loose pulley, respectively, M M', being placed at a convenient point thereon for belt-connection with a line of shafting.

In order that articles of different thicknesses 50 may receive substantially the same pressure from the plunger, a spiral spring, J', is placed

in the slotted or open portion of the bearing j of the pitman J, which in this case would be formed separate from said pitman J and surrounding the cylindrical end of the said pitman, upon which is secured a collar, j', one end of said spring bearing against the said collar and the other against a portion of the bearing j, thus permitting the positive motion of the crank K without interference with the 55 equalizing or yielding action of the pitman and plunger.

If found more desirable, that end of the pitman J containing the spring J' may be attached to the cross head, instead of the crank, 65 with equally as good results. The wringing device consists of two rubber-covered rolls, the lower, N, of which extends partly below the top of the partition in the starch-box, and is permanently mounted, by means of bearings 70 O, upon either the top of the starch-box A or an extension-shelf, A', as seen best in Fig. 2. Underneath this roll is a cavity, P, and a passage, p, extending the whole width of the starch-box and connecting with its interior, for 75 a purpose to be hereinafter explained. The upper roll, N', is mounted in arms or levers R, pivotally connected at either to the starch-box or a portion of the supporting-frame, and provided upon their free ends with suitable 80 counter-weights, R', in order that the said roll may rise, when not required for use, to the position indicated by dotted lines in Fig. 1. To one end of each roller-shaft is secured a suitable spur-gear, S, and when the rolls are 85 in position for use these will mesh together. On the opposite end of the upper roll-shaft is mounted a flanged pulley, T, which connects by a belt, t, with the flanged pulley T' on the driving-shaft L. The length of this belt is 90 such that when the roll N' is brought down and secured in its position over the roll N, it is set in motion; but the moment it is elevated, as before stated, its rotation is stopped.

A narrow cover, U, is provided, which, for 95 convenience, may be hinged, as shown, to the cover a of the box A. This may be readily fastened down by bringing the buttons U' into the position seen in Fig. 2.

Having described the various parts comprising my improved machine, I will now explain its operation.

If, for instance, it is desired to starch a shirt, the operator will first remove the buttons *r* from the levers *R* and the buttons *U'* from the cover *U*, then fold the shirt in such manner 5 that the bosom and cuff-bands may be inserted in the box through the opening left by the said cover, leaving as much as possible of the body of the shirt resting upon the shelf *A'*. The cover *U* should then be fastened down to o prevent the starch from working up and out of the box. The machine may then be set in motion.

The plunger *C* may make fifty strokes (more or less) per minute, and its surface, as well as 5 that of the partition in the box *A*, is provided with a padding, *V*, of felt or other suitable material, in order that any small hard substance—such as buttons—may not be broken while an article is undergoing treatment, and o also as a protection for the surfaces which come in contact, said padding being easily removed for renewal when desired. When the plunger shall have made a sufficient number of strokes to thoroughly impregnate the 5 goods with starch, the machine should be stopped and the cover *U* may be again raised and the roll *N'* brought down and secured, as seen in full lines, Fig. 1, thus causing the belt *t* to become sufficiently taut to rotate the wringing-rolls, and while the shirt is being removed 55 from the starch-box by said rolls all surplus starch, after being squeezed therefrom, is allowed to pass into the cavity *P*, and thence, by means of the passage *p*, to unite again with that in the box *A*.

It may be stated that the buttons *r* are piv-

oted on the extension-shelf, and swing in a horizontal plane. As to the partition, it extends entirely across the starch-box, and should be located away from the end of the box, so as 40 to form the drip-passage shown, so that the starch dropping from the clothes passing through the rolls may return to the box. The plunger should have its throw arranged so as to cause it to properly act upon the garments 45 coming between it and the partition, and should extend entirely across the starch-box.

Having described my invention, what I claim as new, and desire to secure by Letters Patent of the United States, is—

1. The combination, with the partition of the starch-box, of the plunger *C*, the upright *D*, the piece *E* and the ways *F*, the rod *G*, the cross-head *H* and its guide-rods *I*, the pitman *J*, the spring and bearing *J'j*, the crank *K*, 55 and the driving-shaft *L*, as set forth.

2. The combination, with the starch-box having a drip-passage, *p*, extending across its entire width and opening into the interior of the box, of the upper and lower rolls, *N N'*, 60 arranged at the top of said passage, the pivoted weighted arms for lifting the upper roll, and the buttons for holding down or releasing said arms, the pulley on the end of the upper roll-shaft, the belt and the pulley on the driving-shaft, as set forth.

In testimony whereof I affix my signature in presence of two witnesses.

JOHN H. TOOF.
